UNITED STATES PATENT OFFICE.

SIDNEY M. BURK, OF PHILADELPHIA, PENNSYLVANIA, ASSIGNOR OF ONE-HALF TO
GEORGE W. HOSFELD, OF PHILADELPHIA, PENNSYLVANIA.

ROTARY CONVERTER.

1,098,557.

Specification of Letters Patent.

Patented June 2, 1914.

Application filed July 20, 1912. Serial No. 710,658.

To all whom it may concern:

Be it known that I, SIDNEY M. BURK, a citizen of the United States, residing in Philadelphia, county of Philadelphia, State 5 of Pennsylvania, have invented certain new and useful Improvements in Rotary Converters, of which the following is a specification.

My invention relates to commutators designed for transforming a uni-directional or direct current into an alternating current and for transforming an alternating current into a uni-directional or direct current. A commutator of this character is very desirable because of the fact that it very frequently happens that a uni-directional current or direct current only is available whereas the work to be done requires an alternating current or vice versa. Commutators of this character have heretofore been designed but they have not met with success commercially by reason of the complexity of their structure which has rendered them very expensive to build and keep in 25 repair.

It is the object of my invention to provide a commutator capable of performing the functions of transforming electric currents as above stated which shall be simple in construction and which may be manufactured economically.

My invention comprehends the combination and arrangement of parts hereinafter described in the specification, pointed out in 35 the claims, and illustrated in the accompanying drawings to which reference may be had for a clear understanding thereof. It will be understood, however, that changes in the details of construction and arrangement of the parts may be made within the scope of the claims without departing from my invention.

In the drawings:—Figure 1 is a sectional view taken transversely of the structure with 45 the portions thereof, upon opposite sides of the plane upon which said view is taken, turned away from each other so that they rest upon the opposite ends of the structure and certain electrical connections being shown; and Fig. 2 is a view showing the commutator shaft in section and the commutator segments and disks in perspective and the portions of the said shaft and said disks being separated from each other and the said

view also showing certain electrical connections and contacts.

Referring to the drawings, *a* designates a shaft and *b* and *c* designate disks of electrical resistance material secured thereon and rotatable therewith. The said shaft *a* may 60 be driven in any suitable manner but should be driven and caused to rotate synchronously with the generator, when an alternating current is being rectified or converted into a direct and uni-directional current. 65

Secured upon each of the disks *b* and *c* are contact members or commutator segments which are situated at equal distances or intervals from each other. These contacts are designated and indicated upon the 70 respective disks by the numerals 1, 2, 3, 4, 5, 6, 7, 8, 9, 10, 11 and 12. Although I have shown twelve segments carried upon each of the respective disks *b* and *c* it should be understood that the number of these segments 75 may be increased or diminished within the limits by two or multiples thereof.

The brushes *h* are in the preferred form electrically connected in groups of three by metallic members *d*, *e*, *f* and *g*, separated 80 from each other by distances equal to that between alternate segments upon the disks *b* and *c*. It should be understood, however, that the number of brushes connected by the members *d*, *e*, *f* and *g* may be varied, 85 depending directly upon the number of segments employed. The contacts *h* should be of less width than the distance between successive segments 1, 2, 3, etc., so as not to short circuit the current. In the drawings 90 95 the segments 3, 5 and 7 upon the respective disks *b* and *c* are connected by the conductors *i* to the respective segments 9, 11 and 1 diametrically situated with respect thereto. The segments 4, 6 and 8 upon the disk *c* are connected with the segments 10, 12 and 2 of the disk *b* by the conductors *k* while segments 10, 12 and 2 upon the disk *c* are connected to the segments 4, 6 and 8 upon the disk *b* by the conductors 1. 100

It will be obvious that for the respective groups of conductors *i*, *k* and *l* I may substitute single conductors each having branches at its opposite ends connected to the several segments 3, 5, 7, etc., as hereinbefore named. 105

The line wires connected to the brushes which are associated and coöperate with the segments upon the respective disks *b* and *c*

I have designated by the letters *m*, *n*, *o* and *p*. The wires *m* and *p* are connected to a source of electricity and the current which is transmitted thereover is a direct current which fact I have indicated by the letters D. C. applied thereto. The wires *n* and *o* are connected to the service line and transmit an alternating current which fact I have indicated by the letters A. C. applied thereto.

Assuming that a direct or uni-directional current is entering the commutator through the line wire *m* and that the commutator disks are in the position indicated in the drawings, it will be seen that the current from the said line will pass from the connection *d* to the segments 3, 5 and 7 and that it then passes along the conductors *i* to the segments 9, 11 and 1 upon the disk *c* and thence to the line wire *n* returning to the opposite disk *b* of the commutator through the wire *o* which is connected to the member *f*. From the latter the current passes to the segments 1, 11 and 9 on the disk *b* and then along the wires *i* to the segments 7, 5 and 3 also on the said disk *b*. From the said segments last mentioned the current passes to the brush connecting member and thence to the line wire *p*. It is apparent, therefore, that the current, when the commutator disks are in the position illustrated, passes directly through said disks. If, however, the shaft *a* with the disks *b* and *c* thereon should be rotated a single step in the direction of the arrows shown thereon in Fig. 1 so that the brush contacts *h* of the respective connecting members *d*, *e*, *f* and *g* would be brought into contact with the next adjacent segments upon the respective disks, it will be seen that the current from the line wire *m* (assuming that it is entering the commutator over the said wire) instead of pausing directly between the diametrically opposite segments upon the disk passes from the segments 4, 6 and 8 thereon over the conductors *k* to the respective contact members 10, 12 and 2 upon the disk *b*. The current then passes from the member *f* to the line wire *c* and returns over the line wire *n* to the member *e* thence to the segments 2, 12 and 10 on the disk *c* from whence it passes over the conductors *l* to the segments 8, 6 and 4 upon the disk *b*, thence to the brush connecting member *g* and line wire *p*. It is apparent, therefore, that if the line wire *n* is supplied with a direct current it will be converted by its passage through the rotating commutators into an alternating current. The frequency of the said alternating current will depend upon the rapidity with which the said commutators are rotated and also upon the distance apart of the segments 1, 2, 3, etc., upon the respective commutator disks *b* and *c*. It will also be understood that when the line wires *m* and *p* or *n* and *o*, as the case may be, are supplied with an

alternating current such current is rectified or converted into a uni-directional or direct current if the reversal of contacts between the respective brushes and commutator segments is in synchronism with said alternating current.

I claim:—

1. The combination of a revoluble shaft, a support of electric resistance material thereon for supporting two series of segments the said series of segments each being arranged in groups, electric conducting means for directly connecting certain of the segments of one group of each series with certain other segments of the same group, and electric conducting means for connecting the segments of the other group of one series with the other group of the other series.

2. The combination of a revoluble shaft, a plurality of disks thereon, a series of segments on each disk, the said series respectively being arranged in groups, means for electrically connecting certain of the segments of one group with certain other segments of the same group on each disk, and means for electrically connecting the disks of the other group upon one segment with the disks of the other group on the other segment.

3. The combination of a revoluble shaft, a plurality of disks supported thereon and revolving therewith, each disk having a plurality of separate segments thereon, the segments on each disk being arranged in groups, means for electrically connecting certain of the segments of one group with certain other segments of the same group upon each disk, means for connecting the group of segments so connected with a source of electricity and with a service line, means for connecting the other group of segments upon one of the said disks with a corresponding group upon the other of said disks, means for connecting the latter group with the service line and with the said source of electricity.

4. The combination of a shaft, a plurality of disks thereon and a similar number of groups of segments upon each disk, the diametrically opposite segments comprising one group upon each disk being electrically connected and the individual segments comprising the second group on one disk being electrically connected to the diametrically opposite segments of the second group upon the other disks, sets of brushes intermittently and successively contacting with said segments, and a source of electricity connected to one brush on each disk, and one brush on each disk being connected to a service line.

5. The combination of a revoluble shaft, a plurality of disks of electric resistance material thereon, groups of segments upon each disk, means for electrically connecting the

segments of one group with the segments of another group upon the same disk, groups of intermediate segments upon each disk, means for electrically connecting the said intermediate segments upon one disk with the corresponding segments upon the other disk, and brushes successively contacting with the alternate segments of each disk, a pair of said brushes being connected to a

source of current and a pair being connected to a service line.

In testimony that I claim the foregoing as my invention, I have hereunto signed my name this 19th day of July, A. D. 1912.

SIDNEY M. BURK.

In the presence of—

GEO. H. WEIDNER,

CARRIE E. KLEINFELDER.
